Primary Examiner — Kimberly Barnes

(57) **CLAIM**

The ornamental design for a cleaning robot as shown and described.

DESCRIPTION

1. Cleaning robot

1.1: Perspective

1.2: Perspective

1.3: Front

1.4: Back

1.5: Left

1.6: Right

1.7: Top

1.8: Bottom

1.9: Enlarged view of reproduction 1.1

1.10: Enlarged view of reproduction 1.2

1.11: Enlarged view of reproduction 1.2

The evenly broken lines in the drawing depict portions of the cleaning robot that form no part of the claimed design; the

(Continued)

dot-dash broken lines shown in figs. 1.1, 1.2, 1.9, 1.10 and 1.11 depict the boundaries of the enlargements that form no part of the claimed design.
